UNITED STATES PATENT OFFICE.

JAMES T. WHITE, OF MERIDEN, CONNECTICUT.

BUSHING FOR BUFFING-WHEELS.

SPECIFICATION forming part of Letters Patent No. 716,325, dated December 16, 1902.

Application filed September 30, 1902. Serial No. 125,422. (No model.)

To all whom it may concern:

Be it known that I, JAMES T. WHITE, of Meriden, in the county of New Haven and State of Connecticut, have invented a new and useful Improvement in Bushings for Buffing-Wheels; and I do hereby declare the following, when taken in connection with the accompanying drawings and the letters of reference marked thereon, to be a full, clear, and exact description of the same, and which said drawings constitute part of this specification, and represent, in—

Figure 1, a perspective view of a bushing having a buffing-wheel constructed in accordance with my invention; Fig. 2, a vertical sectional view through the bushing and a portion of the wheel enlarged; Fig. 3, a perspective view of the inside of one of the members of the bushing; Fig. 4, a perspective view of the frictional bushing detached; Fig. 5, a perspective view of the clamping-washer; Fig. 6, a perspective view of the clamping-nut; Fig. 7, a perspective view of the bushing-washer and nut in their connected positions.

This invention relates to an improvement in bushings for buffing-wheels, and particularly to wheels which are made from disks of cloth, leather, or other suitable material, to the surface of which buffing-rouge or other abrading or polishing substances are applied. In wheels of this character, which are to be mounted upon a tapered spindle, the center of the wheel or bushing is formed from leather or substance of like character which will hold the wheel on the spindle. These bushings are glued in the center of the wheel and become worn before the face of the wheel is destroyed, and it has been necessary to cut these bushings out and replace them with other bushings; but more or less difficulty is experienced in arranging the new bushings concentric with the wheel.

The object of this invention is to provide a bushing which may be readily inserted through and removed from a wheel, which bushing shall contain a core of leather or other suitable material, adapting the wheel to be placed upon a tapered spindle.

My improvement also provides a construction which permits the same wheel to be applied to a threaded spindle; and the invention

consists in the construction as hereinafter described, and particularly recited in the claims.

The buffing-wheel A is made up of disks of cloth, leather, or other suitable material in the usual manner. Through the wheel is a central opening B, through which my improved bushing extends. This bushing is formed in two parts C, each forming a half of the bushing and each consisting of a body D, a flange E, and a reduced outer end F, which forms a shoulder G. The reduced end F is provided with external threads H and internal threads I. The body is formed with a tapered recess J, in which is an annular rib K and a longitudinal rib L. A frictional bushing M, of leather or other suitable material, tapering longitudinally and corresponding in size to the chambers J and formed with a longitudinal hole N, is placed in the chamber J and the two parts C pressed together to inclose it, the ribs K and L entering the frictional bushing M, so as to lock it in position. Preferably a washer O will then be placed over the body D and against the inner face of the flange E, so as to hold the two parts together. The bushing is then inserted through the hole B in the center of the wheel and a nut P applied over the reduced end F and against the shoulder G, this nut forming a flange corresponding substantially in diameter to the flange R at the other side of the bushing. This nut not only serves to clamp the wheel but also interlocks the two members of the bushing together. The threads I of the two members provide means for mounting the wheel upon a threaded spindle, while the frictional bushing M adapts the wheel to be mounted upon a tapered spindle. When this frictional bushing becomes worn, the nut P may be readily removed, permitting the bushing to be withdrawn from the wheel, the parts separated, and a new frictional bushing inserted and the device replaced. This assures that the bushing shall be concentric in the wheel and can be applied in a few moments and avoid the necessity of waiting for glue to dry, as is the case when the bushing is glued in the wheel.

Having fully described my invention, what I claim as new, and desire to secure by Letters Patent, is—

1. A bushing for buffing-wheels consisting

of two members adapted to be clamped together, said members forming a chamber, and a frictional bushing mounted in the said chamber, substantially as described.

5 2. A bushing for buffing-wheels consisting of two members forming a chamber having annular and longitudinal ribs, means for clamping the two members together, and a bushing in said chamber, substantially as described.

3. A bushing for buffing-wheels consisting of two members together forming a chamber

and a longitudinally-threaded hole, means for clamping the members together, and a frictional bushing located in said chamber, 15 substantially as described.

In testimony whereof I have signed this specification in the presence of two subscribing witnesses.

JAMES T. WHITE.
